Edmund Talbert

Attorney

UNITED STATES PATENT OFFICE.

CHRISTIAN J. WINTER, OF DUBUQUE, IOWA.

INVISIBLE TROUSER SUPPORTER.

Application filed June 9, 1922. Serial No. 566,995.

To all whom it may concern:

Be it known that CHRISTIAN J. WINTER, a citizen of the United States of America, residing at Dubuque, in the county of Dubuque and State of Iowa, has invented new and useful Improvements in Invisible Trouser Supporters, of which the following is a specification.

The object of the invention is to provide 10 a construction of suspenders or trouser supporter which may be worn under the outer or dress shirt for concealment thereby, and in that connection to provide a device which while adequately and comfortably 15 supporting the trousers is adapted to yield readily to the movements of the body of the wearer to avoid straining the garment or causing inconvenience to the wearer; and with these objects in view the invention consists 20 in a construction and combination of parts of which a preferred embodiment is shown in the accompanying drawings, wherein:—

Figure 1 is a front view of a supporter 25 embodying the invention arranged in the operative position with the wearer and the garment supported thereby indicated in dotted outline.

Figures 2 and 3 are detail views respectively 30 of the front and one of the side attaching means and the adjacent portions of the webbing.

The shoulder straps 10 consisting of elastic webbing or the equivalent thereof are 35 provided with suitable adjusting buckles 11 and connected at their front ends by an equalizing element consisting of a bar 12 having terminal engagement by means of rings 13 with the slides 14 engaged in the 40 loops of the shoulder straps.

Connected with the equalizing bar with 45 each of the shoulder straps at its rear end, through the medium of a suitable loop 15, is a clasp 16 constructed of a single blank 50 of wire or its equivalent doubled upon itself at its center to form an attaching eye 17 and having return side arms 18 forming loops with the main stem 19 and terminating in clips 20 adjacent to the transverse 55 plane of the attaching eye 17 and adapted

for engagement with the buttons attached to the inner surface of the trousers band as indicated at 21. The clasp which is connected with the equalizing member 12 is adapted to have its clips engaged with the 55 foremost or inner front trousers buttons, the said clasp by reason of the loose connection afforded by an attaching eye 17 being adapted to be brought to the outside of the shirt through the front opening 60 thereof. The clasps which are connected with the other or rear ends of the shoulder straps are adapted for engagement with the buttons at the sides of the trousers band. The shoulder straps are connected at the 65 back of the wearer below the points of bearing on the shoulders of the wearer by a retaining strap 22 having an adjusting buckle 23 for varying the length thereof and having adjustable connection with the 70 shoulder straps by means of slides 24 or the equivalents thereof adapted to slide on and longitudinally of the shoulder straps. This retaining strap, as will be obvious, is intended to hold the shoulder straps in proper 75 positions on the shoulders of the wearer and resist any tendency of the attachment of the rear ends of the shoulder straps to draw the straps outwardly on the shoulders by reason of the connection of their lower ends 80 with the buttons at the sides of the trousers. The elements of the clasps at the closed ends of the loops 16 are engaged by sleeves 25 to hold them in proper relation.

It will be obvious that the equalizing bar 85 12 is free to move angularly or to tilt as well as to move bodily so as to compensate for movements of the body of the wearer and avoid restrictive strains or confinement involving discomfort.

Having described the invention, what is 90 claimed as new and useful is:—

A garment supporter of the type indicated having shoulder straps, an equalizing element connecting the shoulder straps at 95 their front ends and provided with a button engaging clasp, button engaging clasps adapted for engagement with buttons at the sides of the garment, the last of said clasps being carried by the rear ends of the shoul- 100

der straps, all of said button engaging clasps consisting each of a single blank of wire doubled upon itself at its center to form an attaching eye and having return side arms and an intermediate stem portion parallel with said side arms and forming loops in connection with the latter, the side arms terminating in upwardly open clips

adjacent to the plane of the attaching eye, and sleeves engaging the loops formed by the side arms to hold said loops in proper relation with the stem. ¹⁰

In testimony whereof he affixes his signature.

CHRISTIAN J. WINTER.
